APPARATUS AND PROCESS FOR CONTINUOUSLY REMOVING VOLATILE MATTER FROM A LIQUID

Arthur U. Ayres, Chestnut Hill, and Nathaniel Brewer, Lansdowne, Pa., assignors to The Sharples Specialty Company, Philadelphia, Pa.

Application March 29, 1934, Serial No. 717,882

10 Claims. (Cl. 159—44)

This invention relates to the art of purifying liquids and was conceived as the solution of problems encountered incident to the continuous refining of fatty oils by a process invented by Edward M. James and described in co-pending applications Serial Nos. 567,220 and 659,918, filed on October 6, 1931, and March 7, 1933, respectively. While the present invention is adapted for use in connection with other processes than that defined in these James applications, the nature of the problem presented and of its solution will be better understood by reference to that process.

In accordance with the method described in the above identified James applications, a fatty oil and alkali are continuously fed in carefully proportioned amounts through a continuous high speed mixing device adapted to effect an intimate contact therebetween, and the mixture of oil and soap-stock formed by the reaction in the mixing device is continuously passed from that mixing device through a continuous heater which rapidly raises the mixture to a temperature which facilitates centrifugal separation of the soap-stock from the neutral oil. The mixture is then passed directly from the heater to a primary battery of centrifugal separators for separating soap-stock from the oil.

Such a method of operation possesses important advantages from the standpoint of avoidance of loss of valuable oil by saponification and entrainment in the soap stock and it effects considerable economies in time, space and equipment. Purified oil passing from this primary purifying system, like purified oil obtained by the more conventional gravity settling process, contains, however, a certain amount of impurities in the nature of aqueous alkali solution and soap-stock. These impurities tend to cause a saponification of the purified oil when they are allowed to remain in contact with it for a prolonged length of time and it is accordingly desirable that they be removed so promptly that deteriorating effects caused by their presence are arrested before substantial damage to the oil has occurred.

To this end the oil discharged from the primary centrifugal separators is passed promptly through apparatus adapted to effect a continuous washing of the oil with warm water. In order to complete the removal of the impurities as promptly as possible, the major portion of the wash water and impurities is then continuously separated from the oil by a secondary battery of centrifugal separators.

In the practice of such a process, the oil discharged from the secondary battery of centrifuges is still contaminated with a small quantity of water and other volatile impurities and such impurities cause deterioration of the oil un-

less promptly removed. The principal object of the present invention has been to provide a method and apparatus by which the removal of these impurities may be rapidly effected in the treatment of oil discharged from a system of this general type.

In connection with a system of this character, the rate of flow of oil through the system is necessarily variable, these variations in flow being due to the curtailment of use of one or more of the centrifuges of the primary or secondary purifying system, or variations in the rate of output with respect to one or more of the centrifuges, and being necessitated by requirements of bowl cleaning, variations in character of the oil under treatment, variations in supply or other factors. Since it is important that impurities which are more volatile than the oil, and particularly water, be removed from the oil without undue delay this variable rate of discharge from the second purifying system presents a difficult problem. A feature of the invention involves the conception of a process and apparatus whereby the rate of passage of the oil to evaporating apparatus for removing these residual volatile impurities may be reasonably accurately co-ordinated with the rate of discharge from the secondary purifying system.

In the form of evaporating apparatus used, the oil or other liquid under treatment is injected in dispersed form through a plurality of nozzles or the like. It is desirable, as described above, that the rate of injection of oil into this apparatus be co-ordinated with the rate of supply of oil from the purifying system. Such co-ordination presents a difficult problem, however, under conditions of curtailed discharge, for substantial curtailment of discharge through a nozzle results in a failure to obtain adequate dispersion incident to such discharge and accordingly results in loss of efficiency in the evaporating operation. A further feature of the invention consists in the avoidance of this difficulty by the use of a plurality of parallel discharge outlets each of which is adapted to discharge liquid into the evaporating chamber in dispersed form, and in the control of such parallel discharge outlets in such a manner as to entirely suspend the injection of liquid through one or more of them upon curtailment of the rate of supply. By operating the system in this manner, it is possible to maintain a substantial volume of discharge through each nozzle through which discharge is taking place during any given stage of the operation, and curtailment of the rate of discharge of the oil from the secondary centrifuges, for example, does not result in the above mentioned difficulties of in-

jection of liquid into the evaporating chamber in inadequately dispersed form.

A further feature of the invention consists in an arrangement whereby liquid is discharged into an evaporating chamber through a plurality of parallel discharge outlets as described above and in which the discharge through every one of said outlets is suspended upon the feed of liquid to the evaporating apparatus at a rate in substantial excess of the rate of discharge therefrom.

The invention will be better understood by reference to the attached drawing when considered in connection with the following detailed description.

15 In the drawing, the single figure is a diagrammatic side elevation of apparatus illustrating the features of the invention.

Referring to the drawing by reference characters, the numeral 10 indicates a centrifugal separator which may be one of a battery of separators adapted to discharge a liquid which has been subject to treatment and which contains undesired volatile impurities. Such liquid may, for example, comprise a fatty oil purified by the James process described above and containing a small amount of residual moisture. The liquid discharged from the purifying system is fed indirectly, as described hereinafter, to an evaporating chamber 11, which may be connected with a 20 vacuum pump or other suitable evacuating mechanism or apparatus. The feed of liquid to the evaporating chamber is co-ordinated with the rate of discharge from the purifying system by the injection of such liquid into the evaporating chamber through a plurality of parallel discharge outlets 13 which are provided with connections in the form of valves 14 which are adapted to be selectively closed in response to curtailment of flow of liquid from the centrifugal separators. 25

30 This result is obtained by passing liquid from the centrifuges 10 into a float tank 15 which contains a heating coil 16 adapted to heat the liquid to a temperature facilitating the evaporation of volatile impurities therefrom upon injection 35 thereof in dispersed form into the evacuated evaporating chamber.

The float tank 15 contains a float 17 which is connected to a float arm 18 which successively controls a plurality of switches contained in a 40 switch box 19 for effecting successive actuation of the valves 14 responsive to the level of liquid within the tank 15. A plurality of mercury contact switches within the switch box 19 may, for example, be successively operative to effect actuation 45 of solenoids 20 successively controlling the operation of valves 14 in response to varying levels of liquid within the tank 15, the solenoids being connected with the switch box 19 through parallel electrical connections 21 forming a part of a 50 circuit 22. The entire circuit 22 is controlled by a switch 23 controlled by a float operating within a float chamber 24 arranged in a conduit 25 forming a by-pass from the main body of the evaporating chamber.

55 In the practice of the invention liquid is discharged into the float tank 15 and heated in that tank. Upon the attainment of a predetermined level in that tank, the float arm 18 rises to a sufficient extent to cause the actuation of one of the 60 switches within the box 19 and the opening of one of the valves 14 through the energization of its associated solenoid 20. The opening of the valve 14 results in the injection of liquid through its associated discharge outlet 13 in dispersed 65 form into the evaporating chamber 11, the flow

of liquid into this chamber being caused by the vacuum within that chamber. If the rate of discharge through the outlet 13 which is operative at this stage of the operation is less than the rate of discharge from the centrifuge 10, the level 5 of liquid in the float tank 15 will continue to rise and will cause actuation of a second switch and associated solenoid and valve to effect discharge of liquid through a second discharge outlet 13. If the feed of liquid is still in excess of the capacity of the two discharge outlets now open, the third discharge outlet will soon thereafter be actuated similarly.

Assuming now that all of the discharge outlets are in full operation and that the rate of supply 15 to the tank 15 is diminished, the float 17 will fall and successively cause closure of one or more of the valves 14, thereby effecting cessation of feed through one or more discharge outlets while maintaining the feed through the remaining discharge outlets of the series at full capacity. It will thus be seen that the problem of correlating the rate of feed to the evaporating apparatus with the rate of discharge of liquid from the refining system or other source of supply is solved 20 without impairment of the efficiency of the evaporating chamber, such as would be involved if a single valve controlled the flow of liquid to the evaporating chamber by throttling, and an attempt were made to effect control of flow of liquid 25 to the evaporating chamber by manual or automatic control of that valve.

In case liquid is fed to the evaporating chamber in substantial excess of its discharge capacity, the float switch 23 will be actuated to open the 35 circuit 22 incorporating the three parallel branches 21 and consequently cause de-energization of all of the solenoids 20 and suspension of flow through every one of the discharge outlets 13. This suspension of flow will continue until 40 the level of liquid in the evaporating chamber has dropped to a sufficient extent to render resumption of flow to the evaporating chamber desirable.

Modifications will be obvious to those skilled 45 in the art and we do not therefore wish to be limited except by the scope of the subjoined claims. While the specific form of the invention described above involves selectively controlling the number of discharge outlets in response to 50 reduced rate of flow of liquid to the evaporating chamber, a partially analogous result may be attained by accumulating a reserve body of liquid and passing the liquid to the evaporating apparatus, at substantial capacity at alternating 55 periods of feed, the feed being entirely suspended between such alternating feed periods. In connection with such a system of operation, the duration of the successive periods of feed and of the periods of cessation of feed would naturally be 60 determined by the rate of supply of liquid to the evaporating apparatus. It will thus be seen that the most important feature of the invention consists in the feed of liquid through the discharge nozzle or nozzles which are operative at any given 65 stage of the practice of the invention at substantial capacity and that alternative methods of accomplishing this result fall within the spirit of the invention.

We claim:

1. In apparatus for continuously removing volatile impurities from a liquid, the combination comprising a dehydrating chamber, a supply tank, means for conducting liquid from said supply tank to said dehydrating chamber, plural 70

parallel means for injecting liquid into said dehydrating chamber in dispersed form, and means controlled by the level of liquid in said supply tank for causing discontinuance of injector of liquid through one or more of said injecting means selectively.

2. In apparatus for continuously removing volatile impurities from a liquid, the combination comprising a dehydrating chamber, a supply tank, means for conducting liquid from said supply tank to said dehydrating chamber, plural parallel means for injecting liquid into said dehydrating chamber in dispersed form, means controlled by the level of liquid in said supply tank for causing discontinuance of injection of liquid through one or more of said injecting means selectively and means for causing discontinuance of injection of liquid through all of said injecting means upon feed of liquid to said dehydrating chamber in substantial excess of its operating capacity.

3. An evaporating apparatus for removing residual volatile impurities from a liquid supplied at a variable rate comprising an accumulating tank, means for feeding said liquid continuously from said accumulating tank to an evaporating chamber and including means for injecting liquid into the evaporating chamber in dispersed form through a plurality of parallel discharge outlets, valve means for causing discontinuance of the discharge of liquid through one or more of said outlets selectively, means operative in response to diminution in the rate of supply of said liquid to the accumulating tank for actuating said valve means to closed position, whereby to maintain substantial volume of discharge through the outlets with respect to which the discharge is not so discontinued.

4. An evaporating apparatus for removing residual volatile impurities from a liquid supplied at a variable rate comprising an accumulating tank, means for feeding said liquid continuously from said accumulating tank to an evaporating chamber, said means including means for injecting the liquid into the evaporating apparatus in dispersed form through a plurality of parallel discharge outlets, and means for causing discontinuance of the discharge of liquid through one or more of said outlets selectively in response to the operation of a float valve controlled by the level of liquid in said accumulating tank, whereby to maintain a sufficient volume of discharge through the outlets with respect to which the discharge is not so discontinued to insure a high degree of dispersion of said liquid.

5. The method of continuously removing volatile impurities from a liquid continuously supplied at a variable rate which comprises subjecting such liquid to a continuous evaporating operation while discharging such liquid continuously in dispersed form at a plurality of parallel discharge points and interrupting the discharge through one or more of said discharge points selectively to maintain the number of discharge points operating at any given stage of operation approximately proportionate to the rate of supply of said liquid.

6. In apparatus for continuously removing volatile impurities from a liquid, the combination comprising a dehydrating chamber, means for conducting liquid to said dehydrating chamber, plural parallel means for injecting liquid into said dehydrating chamber in dispersed form and means for causing discontinuance of injection of liquid through one or more of said injecting

means selectively in response to diminution in rate of supply of said liquid to the purifying apparatus, whereby to maintain a substantial volume of discharge sufficient to effect a high degree of dispersion of liquid through each of the injecting means through which discharge is not so discontinued.

7. In apparatus for continuously removing volatile impurities from a liquid, the combination comprising a dehydrating chamber, means for conducting liquid to said dehydrating chamber, a plurality of parallel discharge nozzles interconnected with said conducting means and projecting into said dehydrating chamber and adapted to effect injection of liquid into said dehydrating chamber in dispersed form, and means for causing discontinuance of injection of liquid through one or more of said discharge nozzles selectively in response to diminution in rate of supply of said liquid to the purifying apparatus, whereby to maintain a volume of discharge sufficient to effect a high degree of dispersion through each of the discharge nozzles through which discharge is not so discontinued.

8. In apparatus for continuously removing volatile impurities from a liquid, the combination comprising a dehydrating chamber, means for supplying liquid at a variable rate, means for conducting liquid to said dehydrating chamber, plural parallel means for injecting liquid into said dehydrating chamber in dispersed form, and means controlled by the rate of supply for causing discontinuance of injection of liquid through one or more of said injecting means selectively in response to diminution in rate of supply of said liquid to the purifying apparatus, whereby to maintain a volume of discharge sufficient to effect a high degree of dispersion through each of the injecting means through which discharge is not so discontinued.

9. In apparatus for continuously removing volatile impurities from a liquid supplied at a variable rate, the combination comprising a dehydrating chamber, a conduit through which liquid is fed to said dehydrating chamber, plural parallel means for injecting liquid into said dehydrating chamber in dispersed form, means actuated in response to diminution in the rate of supply for causing discontinuance of injection of liquid through one or more of said injecting means selectively, whereby to maintain a substantial volume of discharge and dispersion through each of the injecting means through which discharge is not so discontinued, and means for suspending injection of liquid through all of said injecting means upon feed of liquid to said dehydrating chamber in substantial excess of its operating capacity.

10. In apparatus for continuously removing volatile impurities from a liquid supplied at a variable rate, the combination comprising a dehydrating chamber, a conduit through which liquid is fed to said dehydrating chamber, plural parallel means for injecting liquid into said dehydrating chamber in dispersed form, a valve associated with each of said injecting means adapted selectively to permit or prevent injection of liquid into said dehydrating chamber through the injecting means controlled thereby, and electrical control means for suspending feed of liquid through one or more of said valves selectively in response to diminution of the rate of supply of said liquid.

CERTIFICATE OF CORRECTION.

Patent No. 2,068,971.

January 26, 1937.

ARTHUR U. AYRES, ET AL.

It is hereby certified that error appears in the printed specification of the above numbered patent requiring correction as follows: Page 3, first column, line 4, claim 1, for "injector" read injection; and that the said Letters Patent should be read with this correction therein that the same may conform to the record of the case in the Patent Office.

Signed and sealed this 20th day of April, A. D. 1937.
